UNITED STATES PATENT OFFICE.

THOMAS CURTIS TUSSEY AND WILLIAM D. SHAW, OF WESTERVILLE, OHIO.

DESIGN FOR A LAMP-LENS.

52,360.

Specification for Design.

Patented Aug. 27, 1918.

Application filed May 2, 1918. Serial No. 232,167. Term of patent 7 years.

To all whom it may concern:

Be it known that we, THOMAS C. TUSSEY and WILLIAM D. SHAW, citizens of the United States, residing at Westerville, in the county of Franklin and State of Ohio, have invented a new, original, and ornamental Design for Lamp-Lenses, of which the following is a specification, reference being had to the accompanying drawing, forming part thereof.

Figure 1 is an elevation of the rear side of a lamp lens embodying our design; and,

Fig. 2 is a cross sectional view through the same.

We claim:

The ornamental design for a lamp lens as shown.

THOMAS CURTIS TUSSEY.
WILLIAM D. SHAW.
